UNITED STATES PATENT OFFICE

JAMES B. PEGRAM, OF BRIDGETON, NEW JERSEY

ALARM

Application filed April 13, 1929, Serial No. 354,925. Renewed March 27, 1930.

The present invention relates to new and useful improvements in signals and more particularly to an alarm of the thermostatic operated type. The principal object of this invention is to provide a simple and economical alarm which will be within the economic demand of the public.

Another important object of the invention is to provide a fire alarm which will be positive and efficient in operation.

These and other important objects of the invention will become more apparent as the present invention is understood from the following specification and claims.

15 In the drawings:—

Figure 1 represents a side elevation of the improved alarm partly broken away to disclose details of construction.

Fig. 2 represents a vertical sectional view 20 taken substantially on the line 2—2 of Fig. 1.

Fig. 3 represents a fragmentary side elevation showing the structure partly broken away to disclose the operable mechanism therein.

25 Referring to the drawings wherein like numerals designate like parts, the invention includes a plate 5 with a flange 6 at its periphery. Projecting from the plate 5 in a direction opposite to the direction of the flange 6 and being vertically spaced, are the bolts 7. The free ends of the bolts are reduced and threaded to receive nuts 8 for securing the elongated plate 9 against the shoulders of the bolts at said reduced ends.

35 Secured to the inner side of the plate 9 are coincidently arranged sensitive thermostatic wafers 10, the innermost wafer 10 having a central protuberance 11 for disposition through an opening 12 in a leaf spring 13.

40 The upper end of the leaf spring 13 has a threaded opening through which is threadedly engaged a screw 14 having a reduced end 15 bearing through an opening in the plate 5. The opposite end of the leaf spring 13 is secured to one end of a plunger 16, which has an outwardly flaring head 17 for engagement with the pawl 18 of a suitable clock spring mechanism, generally referred to by the numeral 19.

50 The plunger 16 has an extension 20 pro-

truding from the head 17 and which is adapted for disposition through an opening in a partition 21. A spring 22 is convoluted on the extension 20 and interposed between the head 17 and the partition 21 and adapted for normally maintaining the head 17 engaged with the pawl 18 for preventing the actuation thereof by the said clock mechanism.

The pawl 18 has a head or clapper 23 which is adapted to engage the bell 24 which provides a cover for the lock mechanism and produces a sound when the plunger head 17 is released by the expansion of the thermostatic wafers 10.

Suitable adjustment of the leaf spring 13 may be obtained by the completing of the screw 14, while the bell 24 may be secured to the plate 5 by any suitable means.

It is to be understood that numerous changes in the specific shape, size, materials, may be resorted to without departing from the spirit and scope of the invention as claimed hereinafter.

Having thus described my invention, what I claim as new is:

1. An alarm comprising a bell, a thermostatic unit, a spring mechanism, a clapper for engagement with the bell and cooperation by said spring mechanism, and means engageable with said clapper and releasable by the said thermostatic unit, said means consisting of a slide rod, a leaf spring engageable by said thermostatic unit, and being connected to said slide rod, and a head on the slide rod for normal engagement with the clapper.

2. An alarm comprising a bell, a thermostatic unit, a spring mechanism, a clapper for engagement with the bell and cooperation by said spring mechanism, means engageable with said clapper and releasable by the said thermostatic unit, said means consisting of a slide rod, a leaf spring engageable by said thermostatic unit, and being connected to said slide rod, a head on the slide rod for normal engagement with the clapper, and spring means on said slide rod for normally maintaining the head engaged against the clapper.

3. An alarm comprising a bell, a thermostatic unit, a spring mechanism, a clapper for engagement with the bell and cooperation by the said spring mechanism, means engageable with said clapper and releasable by the said thermostatic unit, said means consisting of a slide rod, a leaf spring engageable by said thermostatic unit, and being connected to said slide rod, a head on the slide rod for normal engagement with the clapper, and means for adjusting the said leaf spring.

In testimony whereof I affix my signature.

JAMES B. PEGRAM.
